UNITED STATES PATENT OFFICE

2,581,837

PROTECTIVE CAP MOLD

Alvis L. Cruise, Marshfield, Mo.

Application December 19, 1947, Serial No. 792,789

8 Claims. (Cl. 18—42)

1

This invention relates to new and useful improvements in molds and the primary object of the present invention is to provide a mold for quickly and readily forming a protective cap that is applied to a pregnant mare for receiving the urinal which is employed in the manufacture of hormones.

Another important object of the present invention is to provide a mold for forming a resilient urinal bag that includes novel and improved means for providing a rounded edge for the bag formed to prevent injury to the animal on which the same is applied.

A further object of the present invention is to provide a protective cap or bag mold that is extremely small and compact in structure and which may be conveniently assembled or disassembled in a minimum time.

A still further aim of the present invention is to provide a protective cap mold that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a group perspective view of the present mold;

Figure 2 is a longitudinal vertical sectional view taken substantially through the center of the present mold in an assembled form; and,

Figure 3 is an end view of the core used in conjunction with the present invention.

Referring now to the drawings in detail, wherein for the purpose of illustration, there is disclosed a preferred embodiment of the present invention, the numeral 10 represents the lower half of the present mold generally, comprising a substantially rectangular body having spaced parallel side walls 12, and end walls 14 and 16. The upper portion of the lower half 10 is provided with an open channel or concavo-convex lower wall 18 that terminates at one end in an arcuate extension 20. The upper arcuate extremity 22 of the extension 20 is integrally formed with a downwardly and inwardly inclined upper wall 24 that is integrally formed with the end wall 14 and the side walls 12, at one end thereof. An open heating chamber 26 is provided in the lower portion of the lower half and may receive electri-

2

cal heating coils or the like for transmitting heat to the lower wall 18 of the lower half. It should be noted, that the upper edges 28 of the side walls 12, adjacent the end wall 16, are spaced parallel to the lower edges 30 of the side walls 12. However, the upper edges 32 of the side walls 12, adjacent the end wall 14, are arcuately formed for a purpose which will later be more fully described.

10 The numeral 34 represents the core used in conjunction with the present invention generally, comprising a preferably hollow cylindrical body 36 having a concavo-convex integral extension 38 at one end that is provided with an arcuate end wall 40. The upper edges 42 of the end wall 40 and the extension 38 are arcuately formed and communicate with the arcuate and outwardly inclined edge 44 at the innermost end of the body 38.

15 20 The numeral 46 represents the upper half of the present mold generally, comprising a pair of spaced parallel side walls 48, and end walls 50 and 52. The lower straight edges 54 of the side walls 48 terminate in lower arcuate edges 56 that are connected by an integral arcuate plate 58 that is also integrally formed with the end wall 50. This plate 58 is provided with an irregular longitudinal opening 60 that conforms to the opening between the arcuate edges 32 of the side walls 12 and the arcuate inner edge of the wall 24.

25 30 Integrally formed with the end wall 52 of the upper half 46, the side walls 48, and the upper inclined extremity 62 of the arcuate plate 58 is a concavo-convex upper wall 64, the upper convex extremity 66 of which is spaced inwardly relative to the upper straight edges 68 of the side walls 48.

35 40 It is preferred, that the aligned end walls 16 and 52 of the upper half 46 and the lower half 10, be provided with arcuate openings 70 facilitating visibility into the core 34 and which will also provide an outlet opening for material entering the said core. The upper half 46 is hollow to provide a heating chamber, and this heating

45 50 55 chamber receives suitable electrical heating coils for transmitting heat to the plate 58 and also the upper wall 64.

In practical use of the device, the material that forms the desired finished product, which is preferably raw rubber, is poured into the lower half and more particularly on the walls 18 and 20 of the said lower half. The core 34 is then inserted into the lower half, so that edge 74 of the body 36 will frictionally engage the end wall 16 of the lower half, and there will exist a space

or plenum chamber 76 between the lower periphery of the extension 38, the lower periphery of the cylindrical body 36 and the walls 26 and 18 of the lower half.

Such a space 76 will define the thickness of the lower portion of the finished product. The upper half 46 is then inserted in position to the lower half 10, so that the plate 58 will frictionally bear against the wall 24, the edges 54 and 56 of the side walls 48 will frictionally engage the upper edges 32 and 28 of the side walls 12, the edge 42 of the extension 38 and wall 48, will frictionally engage the arcuate plate 58, the edge 44 of the cylindrical body 36 will frictionally engage the upper extremity 62 of the arcuate plate 58, and the upper periphery of the edge 74 of the core will frictionally engage the end wall 52 of the upper half. A further space or plenum chamber 78 is provided between the upper periphery of the cylindrical body 36 and the upper wall 64 of the upper half. This further chamber 78 communicates with chamber 16, and defines the thickness of the upper portion of the finished product.

Opposed rigid ears 80 and 82 carried by the end walls of the upper half and lower half receive fasteners or the like 84 for removably securing the upper half relative to the lower half.

Arcuate grooves 86 and 88 are provided in the upper wall 64 and the lower wall 18, adjacent the end walls 52 and 16, respectively, to provide an annular beading about one end of the finished product. There is also provided complementary and communicating grooves 90 and 92 in the opening 60, the inner face of the plate 58, and the upper inner, arcuate edges of the side walls 12 and the wall 24, that will provide a further beading or lip about the remaining edges of the finished product.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having thus described the invention, what is claimed as new is:

1. A mold for forming a protective cap that is applied to pregnant mares for receiving a urinal, said mold comprising upper and lower mold members, said mold members having exterior depressions defining heating chambers, a core interposed between said mold members and having an arcuate opening therein, said upper mold member having a lower concavo-convexed wall bearing against the edges of said core defining said arcuate opening when a plastic material is charged in the mold about the core, said mold members having first and second end walls, said core having an end abutting the first end walls of said mold members as a plastic material is charged in the mold about the core, said lower mold member having a concavo-convexed lower wall conforming to the contour of the lower periphery of said core, said upper mold member having an upper concavo-convexed wall spaced from said core and fixed to said lower concavo-convexed wall, and means securing the mold members together.

2. The combination of claim 1 wherein said core is hollow and the said end of said core is opened, the first end walls of said mold members having openings communicating with the interior of said core and providing outlet openings for material entering the core.

3. The combination of claim 1 and a first channel provided in the inner surface of the upper wall of said upper mold member, and a further channel provided in the inner surface of the lower wall of said lower mold member communicating with said first channel to form a beading about one end of the finished article.

4. A mold for forming a protective cap that is to be applied to pregnant mares for receiving a urinal, said mold comprising upper and lower mold members, said lower mold member having an upper wall with an elongated recess therein, said upper mold member including a hollow depending portion in registry with the recess, means connecting the mold members, and a core slidably received in said recess and including an arcuate extension having a continuous edge engaging the depending portion of said upper mold member as a plastic material is charged in the recess about the core.

5. A mold comprising upper and lower interconnected mold members and a core interposed between and removable from the mold members, said lower mold member including an upper wall having a longitudinal recess therein and an end wall, said upper mold member including a hollow depending portion in registry with the recess and contacting the upper wall of said lower mold member, said upper mold member also including an end wall supported on the end wall of said lower mold member, said core being hollow throughout its length and having an end engaging the end walls of said mold members, said core being disposed within the recess and including a concavo-convexed extension for engaging the depending portion of said upper mold member as a plastic material is charged in the recess and about the core.

6. A protective cap mold comprising upper and lower mold members; said lower mold member having first and second end walls and a pair of side walls; an upper wall integrally formed with the second end wall of said lower mold member; a concavo-convexed lower wall integrally formed with said upper wall, said side walls and said first end wall; said upper mold member having a pair of side walls and first and second end walls; the end walls of said upper mold member engaging and being supported on the end walls of the lower mold member; an elongated concavo-convexed plate integrally formed with the second end wall of said upper mold member and the side walls thereof and having a portion contacting the upper wall of said lower mold member; a concavo-convexed upper wall integrally formed with the first end wall of said upper mold member and the side walls thereof; said concavo-convexed upper wall being integrally formed with said plate; a sleeve-like core positioned between said upper and lower mold members and having one end abutting the first end walls of the mold members; said core having an arcuate extension at its other end; said extension having a continuous edge adapted to abut the under surface of said concavo-convexed lower wall of said lower mold member as a plastic material is charged between said mold members and about the core; and means detachably securing said mold members together.

7. The combination of claim 6 wherein said core is hollow throughout its length, and outlet openings provided in the first end walls of said mold members for excess plastic material entering the core.

8. The combination of claim 6 wherein said upper concavo-convexed wall includes a groove of uniform depth in its concave surface; said lower wall of said lower mold member also having a groove of uniform depth in its concave surface communicating with the groove in said upper concavo-convexed wall to form a channel for plastic material charged in the mold about the core; said grooves being disposed adjacent the first end walls of said mold members.
